Primary Examiner — Thomas Johannes*Assistant Examiner* — Shawn T Gingrich(74) *Attorney, Agent, or Firm* — Cermak Nakajima & McGowan LLP; Tomoko Nakajima(57) **CLAIM**

The ornamental design for an adapter for optical connectors, as shown and described.

DESCRIPTION

FIG. 1 is a front elevational view of an adapter for optical connectors showing our new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a bottom plan view thereof.

FIG. 7 is a front and top perspective view thereof;

FIG. 8 is a rear and top perspective view thereof;

FIG. 9 is a front and bottom perspective view thereof; and,

FIG. 10 is a rear and bottom perspective view thereof.

The broken line portion of the figure drawings is included to show portions of the article that form no part of the claimed design.

The dash-dot line represents the boundary of the claimed design.

1 Claim, 10 Drawing Sheets(56)
